UNITED STATES PATENT OFFICE.

ABRAHAM MINTZ, OF NEW YORK, N. Y.

IRONING-BOARD.

1,380,234.

Specification of Letters Patent. Patented May 31, 1921.

Application filed June 23, 1920. Serial No. 391,090.

To all whom it may concern:

Be it known that I, ABRAHAM MINTZ, a citizen of the United States, and a resident of the city of New York, borough of Manhattan, in the county and State of New York, have invented a new and Improved Ironing-Board, of which the following is a full, clear, and exact description.

The present invention relates to new and useful improvements in ironing boards, and it pertains more particularly to devices of this character especially adapted for ironing clothes.

It is one of the primary objects of the present invention to provide an ironing board support so constructed as to permit use of the ironing board with garments of all types, at the same time providing ample room beneath the board for receiving that portion of the garment not operated upon.

It is a further object of the invention to provide an ironing board and support therefor which is capable of end for end reversal.

It is a further object of the invention to so construct the ironing board that regardless of the position of the board with respect to its support, it will be locked against movement so long as the board is parallel with the support.

A further object of the invention is to cover the board with sheet metal in order that the same may be rendered fireproof.

It is a still further object of the invention to form a base or support for ironing boards cast from a single piece of metal.

With the above and other objects in view, reference is had to the accompanying drawings, in which—

Figure 1 is a side elevation of an ironing board constructed and arranged in accordance with the present invention;

Fig. 2 is a sectional view taken on the line 2—2 of Fig. 1, showing the board in dotted lines, and

Fig. 3 is a vertical sectional view taken on the line 3—3 of Fig. 1.

Referring more particularly to the drawings, the reference character 5 designates the base, and said base is constructed of a casting, the marginal edge of which is provided with flanges 6. The upper edge 7 or board-receiving edge of the base is longer than the

lower edge 8 thereof in order that sufficient support for the board may be provided. 55 Projecting oppositely from each end of the lower edge 8 of the base are ears 9, provided with slots or cut-out portions 10 for the reception of bolts 11, by means of which the base is secured to the table or bench not 60 shown in the present invention.

The base 5 is undercut as indicated by the reference character 5'. By this construction it will be seen that ample room is provided to permit of a skirt or similar article being 65 passed over the board to a position where it may be used without bunching or wrinkling that portion of the skirt beneath the board.

The upper edge 7 of the base is cut out as indicated at 12, to provide a recess, and extending downwardly through the base at a point beneath the recess 12 is a passageway 13. At one end of the upper edge 7 of the base is an integral lug 14, which extends transversely of the end of the base as shown, 70 while at the other end there is a similar transversely extending integral lug 15. Branching off from the lug 15, preferably centrally of its ends, is a lug 16, and said lug 16 extends parallel with the longitudinal axis of the base as shown.

The board 17 has secured on its under face substantially centrally of its ends, a transversely-extending bar 18. The bar 18 is secured to the ironing board in any desired 85 manner, such as by means of bolts or the like 19. As clearly shown in Fig. 3, the board 17 is covered with a sheathing of sheet metal or the like 30, to protect the same against heat, thus rendering it fireproof. 90

Secured to the board and projecting downwardly into the recess 13, is a screw-threaded bolt 20, and said screw-threaded bolt 20 is adapted to receive a wing nut 21. To accommodate the wing nut 21, the base 5 is 95 provided with a cut-out portion 22 in which the wing nut travels, and at the base of the cut-out portion 22, the passage 13 is enlarged as indicated at 23. Interposed between the lower face of the wing nut 21 and the bottom of the enlarged portion 23 of the passage 13, is a coil spring 24, the purpose of which will be hereinafter described.

The ironing board is cut out at one of its ends as indicated at 26, and at its other end 105 as indicated at 27, and these cut-out portions

are adapted to receive the integral lugs 14 and 15 heretofore mentioned on the upper edge of the base 5.

The device operates in the following 5 manner:

With the parts in the position shown in Fig. 1, when it is desired to reverse the board, the wing nut 21 is loosened or screwed downwardly of the threaded member 20. This action permits of a vertical 10 movement of the ironing board 17 until the lugs 14, 15, and 16 pass out of their respective cut-out portions 26 and 27, and the member 18 clears the wall of the recess 12.

With the parts in this position, it will be seen that the ironing board 17 will be free 15 to move about the central portion until its ends may be reversed, in which position the cut-out portion 26 of the board will receive 20 the transverse lug 15, and the cut-out portion 27 thereof will receive the transverse lug 14, the transverse brace 18 being turned end for end within the recess 12. If, now, 25 the nut 21 be tightened, it will be seen that the board will be prevented from lifting relatively to the base 5, and will therefore be incapable of reversal until the nut 21 is again loosened.

By this construction it will be apparent 30 that the present invention provides means whereby an ironing board may be supported

rigidly with respect to a table or other suitable support and that means is provided whereby the ironing board may be reversed when desired.

35

Furthermore, it will be seen that by undercutting the board as at 5', the use of a special board for the purpose of pressing garments of the type of skirts, is dispensed with, thereby making the board disclosed in 40 the present invention of universal use.

By providing the spring 24, it will be seen that the nut 21 is prevented from working downwardly of the screw-threaded member 20 to a point where proper setting of 45 the board 17 on the base 5 would be prevented.

I claim:

In a device of the character described, a base provided with a vertically-extending 50 passage having a cut-out portion intermediate of its ends, an ironing board pivotally mounted on the base, a screw-threaded member carried by the ironing board and projecting through said vertical passage, a 55 nut carried by the screw-threaded member and adapted to engage the base to secure the board against movement relative to the base, and a coil spring surrounding said screw-threaded member and interposed between the nut and a portion of the base.

ABRAHAM MINTZ.
